UNITED STATES PATENT OFFICE.

EMIL SCHATZ, OF FRANKFORT-ON-THE-MAIN, GERMANY.

AUTOMATIC APPARATUS FOR GAS ANALYSIS.

No. 895,798.

Specification of Letters Patent.

Patented Aug. 11, 1908.

Application filed March 5, 1906. Serial No. 304,283.

To all whom it may concern:

Be it known that I, EMIL SCHATZ, a subject of the German Emperor, and resident of Frankfort-on-the-Main, Danneckerstrasse 39, Germany, have invented certain new and useful Improvements in Automatic Apparatus for Gas Analysis, of which the following is a specification.

The present invention refers to improvements made in the apparatus described in the specification of my application No. 304,282 filed March 5, 1906 and its object is to obtain an exact automatic registration of the results of an analysis, while the latter is being made. These results are realized by different special arrangements of the apparatus. First of all, the form of the measuring chamber is such that it permits of a quiet entering of the gas to be analyzed into the bell; further, the lever or beam, carrying the bell on one of its arms, supports on its other arm the inscribing stylus of the registering device; a weight mounted on the needle of this beam automatically compensates for the increase in the weight of the bell as it rises out of the liquid, and finally, a float, regulated by the liquid which at the same time serves to obtain a tight joint, effects the return of the bell into the liquid which surrounds it.

30 The annexed drawing, given by way of example, shows diagrammatically two forms of my improved apparatus.

Figure 1, is a sectional view illustrating the invention. Fig. 2, is a view similar to Fig. 1, illustrating a modified form.

In Fig. 1, *a* is the gas inlet-pipe, connected with the gas supply, (the flue of a furnace chimney, etc.); *b* is an injector connected with a water supply pipe; *c* is a pipe branched 40 on the gas supply pipe *a* and leading into the measuring chamber *d*; *e* is a tank designed to receive the displacing liquid; *g* is the pipe which establishes communication between the measuring chamber *d* and the vessel *h* intended to receive the absorption liquid; *i* is a coil filled with the absorption liquid, by means of the passages *j*, and into the lower extremity of which the pipe *g* opens, while its upper extremity extends into the interior of 50 the bell *k*. The capacity of the latter is the same as that of the measuring chamber *d*; it

is situated in a vessel *l*; *s* is a water cistern into which a water inlet-pipe connected with the injector *b* enters; this cistern is provided with an over-flow pipe *t*; *u* is a pipe connecting the cistern *s* with the tank *e* which receives the displacing liquid.

Now, according to the present invention, the measuring chamber is made in the form of a bottle, and is placed exteriorly of the tank *e*, while the bottom of the measuring chamber is connected by a pipe 4, with a chamber *f*, which is situated at the side of and is in communication with the tank *e*. A pipe 5, opening into the chamber *f*, serves to automatically withdraw the liquid from the tank *e*, when the liquid has risen to the bend of the pipe 5. The gas inlet-pipe *c* extends to near the bottom of the measuring chamber *d*, so that, when the lower extremity of 70 this pipe is sealed by the liquid, the measuring chamber contains exactly 100 cubic centimeters of gas.

One of the arms of the lever or beam *o* which is pivoted as at *o'*, carries the bell *k*, 75 while the stylus of the registering device is suspended from the other arm; this latter arm also carries a weight 6 which serves to balance the weight of the bell *k* submerged in the liquid. As is shown in the drawing, 80 the needle of the beam *o* forms an obtuse angle with the arm carrying the bell, and this needle is provided with a weight 7, so that the increase in weight of the bell, which takes place in proportion as it comes out of 85 the liquid, is compensated for. Finally the casing inclosing the apparatus supports at 10 the axis of oscillation of a lever 8, the shortest arm of which carries a weight 9, while the longer arm is provided with a float 11 which 90 plunges into the tank *e*; the free end of this lever 8 comes down into contact with the arm of the lever *o* carrying the bell.

The working of the apparatus constructed in the manner described, is as follows: 95 When the level of the displacing liquid falls in the tank *e* and in the measuring chamber *d* communicating with this latter the gas which has just been analyzed will escape from the bell *k*, in view of the fact that the lower 100 end of the connection pipe *g* has become unsealed in the tank *e*. Simultaneously, the

gas to be analyzed is aspirated by the pipe *c* into the measuring chamber *d*. When the liquid again rises in the tank *e* and the measuring bottle *d*, it seals first of all the lower 5 end of the gas inlet-pipe *c*, thus inclosing 100 cubic centimeters of fresh gas in the measuring bottle, under substantially atmospheric pressure. As the displacing liquid continues to rise, this column of gas is forced 10 into the absorption chamber and from this into the bell *k*; this latter rises in consequence, so that the style of the registering device is lowered to a corresponding extent and registers the amount of the absorption, 15 as well as the final result. The registration of the result is thus made in the course of the analysis itself. Now, to effect a regular and certain registration, the upper part of the measuring chamber *d* is made narrow, and 20 the pipe opening into the bell is contracted in the form of a twyer, with a view to obtain a slower and quieter entering of the gas into the bell.

In proportion as the bell rises under the 25 influence of the pressure of the gas to be analyzed and emerges from the liquid, its weight increases; but at the same time the arm of the lever carrying the bell is lifted, and the weight 7, mounted on the needle of 30 the lever, deviates to the opposite side, and this, the more so, as the bell rises higher. Consequently, by means of the weight 7, the automatic compensation of the increase or the decrease of the weight of the bell is obtained. To force the bell back again into the liquid, with a view to expel the gas which 35 has just been analyzed, the arm of the lever 8, oscillating on a spindle mounted in the casing inclosing the apparatus, presses from 40 above against the arm of the lever *e* carrying the bell, under the influence of the float 11 sinking in the tank *e* which is now empty. On the next rising of the liquid in the tank *e* and of the renewed forcing back of the fresh 45 gas from the measuring chamber into the bell, the float 11 is again lifted and the pressure of the arm of the lever 8 on the arm of the lever *e* is removed, which permits of the free rising of the bell.

50 The apparatus represented in Fig. 2 of the drawing is in all respects similar to that shown in Fig. 1, except that it has undergone certain slight modifications suggested by practice. Thus, the chamber *f* is dispensed 55 with, and the ends of the pipes 4 and 5 lead directly into the tank *e*. The measuring chamber *d*, is made in a cylindrical form, and in the pipe *g* through which the gas is forced, a ball or non-return valve is introduced.

60 The counterpoises 6 and 9 of the beam *o* and of the lever 8 are dispensed with. Finally, two traps 15 and 16 on the feed-pipe *a* are provided one on each side of the branch *c*.

These traps are provided with sealed over-flow pipes. But these traps serve at the 65 same time as safety valves. In fact, if the gas inlet were obstructed, the injector *b* would draw air through the traps 15, 16, which would indicate that the said inlet-pipe is obstructed. If these traps were not there, 70 the injector, in case of obstruction of the pipe, would draw water from the chamber *d* through the pipe *c* and the partial vacuum which would thus be formed in the chamber *d* would cause the absorption liquid of the 75 vessel *h* to enter thereinto.

I claim.

1. In combination, a measuring chamber, 80 means for supplying gas to the measuring chamber, an absorption chamber, a connection between the measuring chamber and the absorption chamber, a tank, a connection between the tank and the measuring chamber, means for filling the tank with a liquid, 85 a bell arranged above the absorption chamber, a connection between the absorption chamber and the interior of the bell, a pivoted lever connected to the bell, a registering stylus carried by the lever, a second lever pressing on the first named lever, and 90 means for relieving the first named lever of the pressure of the second named lever.

2. In combination, a measuring chamber, 95 means for supplying gas to the measuring chamber, an absorption chamber, a connection between the measuring chamber and the absorption chamber, a tank, a connection between the tank and the measuring chamber, means for filling the tank with a liquid, 100 a bell arranged above the absorption chamber, a connection between the absorption chamber and the interior of the bell, a pivoted lever connected to the bell, a registering stylus carried by the lever, a second lever pressing on the first named lever, and means 105 operative within the tank for relieving the first named lever of the pressure of the second named lever.

3. In combination, a measuring chamber, 110 means for supplying gas to the measuring chamber, an absorption chamber, a connection between the measuring chamber and the absorption chamber, a tank, a connection between the tank and the measuring chamber, means for filling the tank with a liquid, 115 a bell above the absorption chamber, a connection between the absorption chamber and the interior of the bell, a pipe communicating with the connection between the absorption chamber and the bell emptying within the 120 tank.

4. In combination, a measuring chamber, 125 means for supplying gas to the measuring chamber, an absorption chamber, a connection between the measuring chamber and the absorption chamber, a tank, means for filling

the tank with a liquid, a connection between the tank and the measuring chamber, a chamber interposed in the connection between the tank and measuring chamber, 5 means acting in conjunction with said chamber for emptying the tank at a predetermined time, a bell arranged above the absorption chamber and a connection between

the absorption chamber and the interior of the bell.

In testimony whereof I have hereunto set my hand in presence of two witnesses.

EMIL SCHATZ.
